COVER FOR PACKAGING CONTAINER
OR THE LIKE

René Dru, 7 Rue du Boccador, Paris, France

Filed Sept. 18, 1967, Ser. No. 8,638

Claims priority, application France June 22, 1967

Term of patent 14 years

(Cl. D9—264)

I claim:

The ornamental design for a cover for packaging container or the like, substantially as shown and described.
